ATTORNEY

UNITED STATES PATENT OFFICE.

CHARLES L. SHELTON, OF COLUMBUS, OHIO.

PACKING-CASE.

SPECIFICATION forming part of Letters Patent No. 712,100, dated October 28, 1902.

Application filed April 6, 1901. Serial No. 54,591. (No model.)

To all whom it may concern:

Be it known that I, CHARLES L. SHELTON, a citizen of the United States, residing at Columbus, in the county of Franklin and State 5 of Ohio, have invented a certain new and useful Improvement in Packing-Cases, of which the following is a specification.

My invention relates to the improvement of packing-cases for glassware; and the objects of my invention are to provide a packing-case of this class of superior construction and arrangement of parts, whereby glassware may be readily and effectively packed within a comparatively small space. These objects 15 I accomplish in the manner illustrated in the accompanying drawings, in which—

Figure 1 is a view in elevation of my improved packing-case with one side thereof removed. Fig. 2 is a sectional view on line 20 $\alpha\alpha$ of Fig. 1. Fig. 3 is a plan view of the case with the top removed. Fig. 4 is a plan view of the bottom frame-tray; and Fig. 5 is a detail view, in perspective, of a portion of the upper packing cover-plate.

Similar numerals refer to similar parts throughout the several views.

In carrying out my invention I employ a box or case of which 1 represents the vertical connected sides, 2 the bottom, and 3 the top. 30 At the junctions of the sides of the casing 1 I provide vertical strengthening cleats or standards 4, and the upper end portions of these corner-cleats are connected by transverse upper and lower strengthening bars or cleats 5 and 6.

In the drawings I have shown my improved packing-case as adapted to contain electric-light globes or other bowl-like bodies. In supporting the lower one of these bowl-shaped 40 bodies, which is indicated at 7, I provide a bottom packing-frame, which consists of two transverse frame-bars 8, which rest upon the bottom of the box 1 and which have secured to their upper sides separated and parallel 45 horizontal frame-boards 9, each of the latter having its inner edge portion provided with a curved recess 10. The edges of these recessed portions have secured thereto radially the corresponding ends of packing-points 11, 50 the pointed terminations of which are adapted to be bent downward, as indicated more clearly in Fig. 1 of the drawings. The pack-

ing-points 11 are preferably formed of strawboard or similar yielding material and the partially-circular seat formed by these radially-arranged packing-points is adapted to receive and support the dome or rounded end portion of the lower bowl-like body 7. This being accomplished, I place upon the upper side of the lower body 7 a packing tray or frame 55 comprising united frame-pieces 12, which form a frame adapted to fit within the casing 1, said frame having secured to its under side a strawboard plate 13. Secured to the under side of this plate 13 is a second strawboard 60 section or plate 15, the latter having an opening therein corresponding with the opening 14 and having projecting inwardly toward the center from the edges of said opening pointed tongues 16, these tongues being adapted, as 65 indicated in Fig. 1 of the drawings, to be bent downward into the mouth of the bowl. The packing-tray is further reinforced by an under side strawboard plate 17, which, as prescribed for the plate 13, is provided with 70 a central opening. This lower strawboard plate 17 adjacent to its central opening bears 75 upon the rim of the next lower bowl 7. It will be observed by reference to Fig. 3 of the drawings that the end portions of the frame-bars 12 are recessed, as indicated at 18, these recesses being adapted to receive the frame-corner-pieces 4. By successively inserting 80 the glass bodies 7 so that their rounded or dome portions are seated in the openings 14 and against the tongues 16 and arranging 85 the packing-trays upon the rims of the bowl-like bodies 7 the packing-case is filled until the rim of the upper bowl-body is adjacent to the top thereof. Upon this top bowl-body is 90 placed a packing-cover or top plate 19, of strawboard or similar material, the latter having secured thereto at desirable points transverse wooden cleats 20, the extended end portions of which are adapted, as indicated more 95 clearly in Fig. 5 of the drawings, to fit into top recesses in the box or casing sides. The packing operation thus being completed, the cover-boards 3 of the case are secured in their positions on the top of said case.

By the above-described operation it will be seen that glass articles similar to those herein described may be quickly and safely packed and that the means employed for supporting 100

and seating said articles are such as to prevent the glass surfaces coming into contact with each other and to assist in retaining said articles in rigid positions within the 5 packing-case.

Having now fully described my invention, what I claim, and desire to secure by Letters Patent, is—

In a packing-case for glass and similar 10 ware, the combination with a box-body 1, of a lower supporting-frame in the bottom of said box and consisting of horizontal frame-pieces 9 having inner edge recesses and packing

points or tongues projecting therefrom, packing-trays adapted to fit and be inserted within 15 said external case, each of said packing-trays comprising a frame and a filling of strawboard or similar material having a central opening and packing-tongues 16 projecting within said openings from its edge portion and a cover for said packing-case, substantially as specified.

CHARLES L. SHELTON.

In presence of—

C. C. SHEPHERD,
P. S. KARSHNER.
